Specification of Letters Patent.

Patented Apr. 6, 1915.

Application filed January 24, 1914. Serial No. 814,085.

To all whom it may concern:

Be it known that I, HARVEY D. WILLIAMS, a citizen of the United States, and a resident of the borough of Manhattan, city, county, and State of New York, have invented certain new and useful Improvements in Gear-Cutting Machines, of which the following is a specification.

My invention relates to machines for cutting gears, and particularly pinions, of a novel character devised by me, certain forms of which are described more fully in my application for Letters Patent filed in the United States Patent Office on April 14, 1913, Serial No. 780,861. The machine herein described may be used to make or cut one or more pinions at one operation. The particular machine illustrated in the main views of the drawings accompanying this application will cut bevel teeth of the type designated as "radial," but in a separate view I have indicated how the machine may be adapted to cut bevel pinions with skew teeth. In either case, the surfaces cut by the machine will have straight lines which are not parallel to the axis of the blank they are cut on.

The cutting tools employed in my machine may be counterparts either of a tooth or of a tooth space of the gear with which the pinion is to mesh, that is to say, in either event, the tool, if it has two cutting edges, will cut two adjacent tooth surfaces of the pinion at the same time, said two cutting edges corresponding to two adjacent or successive tooth surfaces of the gear with which the product of the machine is to mesh.

Reference is to be had to the accompanying drawings, in which—

Figure 1 is a vertical section, taken on lines 1—1 of Figs. 2 and 2^a, through a portion of one form of my improved machine, with parts omitted; Fig. 1^a is a detail vertical section of certain parts, taken on the line 1^a—1^a of Fig. 1; Figs. 2 and 2^a are partial plan views of the machine, with parts broken away so as to better disclose those located under them, and other parts omitted for the sake of clearness; Fig. 3 is a bottom view of one of the cutter-carrying slides and the parts adjacent thereto; Fig. 4 is an end view of the same parts as those shown in Fig. 3, looking in the direction of the arrow 4 in Fig. 1, with parts in section on the line 4—4.

of Fig. 3; Fig. 5 is a bottom view, looking in the direction of the arrow 5 in Fig. 1 and showing a portion of the rotary table or tool-carrier forming part of the machine; Fig. 6 is a section substantially on line 6—6 of Fig. 5; Fig. 7 is a face view of a toothed head used in connection with the machine; Fig. 8 is a partial vertical section, substantially on line 8—8 of Fig. 2^a; Fig. 9 is an enlarged detail vertical section, substantially on line 8—9 of Fig. 2^a; Figs. 10 and 11 are horizontal sections on lines 10—10 and 11—11 respectively of Fig. 9; Fig. 12 is a partial end or face view of a pinion such as is produced with the aid of this machine; Fig. 13 is an enlarged end view of a tooth of such pinion, looking in the direction of the arrow 4 in Fig. 1, and showing also in outline the cutter for shaping said tooth; Figs. 14 and 15 are respectively, a partial plan view or face view and an edge view or side elevation (with parts in section) of the gear with which the said pinion is adapted to mesh; Fig. 16 is a corner view of the upper end of the cutter, looking substantially in the direction of the arrow 16 in Fig. 3; Fig. 17 is a side view (looking in the same direction as in Fig. 4), showing a cutter of a shape different from that illustrated in Figs. 1, 3, and 4; Figs. 18 and 18^a are views similar to Fig. 17, but showing two cutters each of which has a single cutting edge, facing to the left and to the right respectively; and Fig. 19 is a partial plan view representing an arrangement for cutting skew bevel teeth.

The machine shown in the drawings comprises a suitable frame or base having a tubular central portion 20 to receive bearings 21 in which is journaled the vertical shaft 22 driven in any appropriate manner, as by bevel gearing 23, 24. Preferably, the connection between the shaft and the gear 23 is loose and detachable, as by providing said gear with a key or feather to fit a longitudinal groove 22' in the shaft, so that the shaft may be withdrawn from the bearings by sliding it upwardly, after disconnecting the parts normally connected with the upper end of the shaft. As shown, the gear 23 has a sleeve 23' connected by screws 23" with a sleeve 23* mounted to turn on the part 20 and supported by a collar 20' screwed on said part. The upper end of the shaft 22

has a vertical crank pin 25 on which is mounted to turn a plate 26 provided with a hub portion 26' normally resting on a crank disk 25' at the lower end of the crank pin 25. At equal intervals vertical pins 27 extend upwardly from the plate 26, being secured, say, by nuts 28; eight such pins would be used in the particular machine illustrated by the drawings. These pins are of circular cross section, but preferably tapered toward their upper ends, for the purpose of facilitating the application or removal of the parts fitted on said pins. Each of the pins 27 receives a bushing 29 having a cylindrical inner surface and an outer surface which is rounded spherically, at least on its lower portion. On this ball-shaped portion is fitted to move a socket member consisting of a top piece 30 and a bottom piece 31, having their inner surfaces curved spherically to correspond to the bushing 29, while their outer surfaces are screw-threaded for connection with rods 32 suitably perforated for the reception of these socket members; each of the latter is preferably provided with a flange 30' and 31' respectively at its exposed end. Similar bushings 33 and socket members 34, 35 with flanges 34', 35' respectively are provided at the other (outer) ends 30 of the connecting rods 32. The bushings 33 at the outer ends of the connecting rods 32 are fitted on normally vertical pins 36, similar to the pins 27 in being of circular cross section and tapered toward their upper ends. One of the rods 32 has at its inner end, a fork 32' engaging a lug 26" projecting from the hub 26'. Cotter pins 37, 38 normally prevent the connecting rods 32, with their socket members 30, 31, 34, 35, and bushings 29, 33, from being withdrawn upwardly from the pins 27, 36. Each of the pins 36 is secured to a plate 36', fastened, as by means of screws 36", to a slide 39, arranged to reciprocate upon a guide 40. For reasons stated hereinafter, I prefer to arrange the pin 36 unsymmetrically with reference to the holes of the plate 36' which are adapted to receive the screws 36". The guide 40 is forked at its outer end, the fork members 40' being provided with alining openings, screw-threaded at their adjacent portions, to receive the threaded portions 41 of trunnion screws, while the remaining portions of said openings are smooth and of a smaller diameter, to receive the smooth portions or shanks 41' of the trunnion screws. The adjacent ends of said screws have angular heads 41" to enable a wrench or the like to be applied for turning and adjusting the trunnion screws, the other ends of said screws being conical, as indicated at 41*, to fit corresponding bearings in brackets or ribs 42. Set screws 40" serve to hold the trunnion screws stationary (after adjustment) relatively to the guide 40, 40'.

The brackets or ribs 42 form part of, or are secured to, a rotary carrier or annular turntable 43, supported by, and mounted to turn upon, a circular track 44 concentric with the shaft 22, said track forming part of 70 the stationary frame. The turntable 43 is formed with an inclined portion 43' at its inner edge, for normally supporting the guides 40 and slides or tool-holders 39 in the inclined position shown, so that the cutting 75 tools 45 carried by the individual slides, will during their inward or working stroke, travel in inclined paths parallel to lines converging toward a point on the axis of the shaft 22. During the outward or return stroke, however, the tool may clear the work, or rather slide over it lightly, owing to the slide 39 and its guide 40 swinging on the trunnions 41*. In order that the individual tools 45 may 85 be adjusted as required, relatively to the respective slides 39, the following arrangement is provided: The tool 45 has a shank 45' of angular cross section, fitted into a holder 46 having an aperture 46' which holds the tool 90 against lateral movement (see Fig. 3) but allows it to be adjusted toward or from the shaft 22, or rather the holder is adjustable in this direction, the shank of the tool fitting partly within a recess 39' of the respective slide 39, and being pressed tightly against the transverse wall of said recess, by means of a set screw 47 passing through the inner portion of the holder 46. The latter is connected adjustably with the slide 39, the 100 outer end of the holder having a screw 46" which fits a corresponding socket 39" of the slide, and the body of the holder is cylindrical as shown in Figs. 3 and 4, the slide 39 having a corresponding recess 39*. The 105 upper end 45" of the tool shank is substantially cylindrical, and on this portion is mounted to turn a nut 48 screwing on the shank and held against longitudinal movement in any suitable manner, as by fitting 110 a portion of the nut between the upper surface of the slide 39 and a confining plate 49 secured to the slide by means of a screw 50, a washer or distance piece 51 being used to prevent the plate 49 from clamping the nut 115 48 against the slide 39. The holder 46 is made adjustable toward and from the shaft 22 so that tools having shanks of different thicknesses may be accommodated. Upon loosening the set screw 47, the nut 48 may be 120 turned to adjust the tool 45 up or down. If it be desired to turn the holder 46 about the axis of the screw 46" in order to adjust it inwardly or outwardly (since by turning the holder its screw 46" will be caused to 125 shift lengthwise in the socket 39", Fig. 1), the tool 45 is removed from the holder; of course, if it should be attempted to turn the holder 46 about the axis of the screw 46" while the tool 45 is in the holder, the engage- 130

ment of the tool with the walls of the recess 39' will prevent the holder from turning (see Fig. 3).

In order that the line in which the tool 5 45 reciprocates may be altered if required, the guide 40 has been made adjustable laterally such adjustment being effected by turning the trunnion screws 41, but the following 10 additional adjusting device is provided: The slide 39 has a dovetail portion 39' (Fig. 4), the flat lower surface of which bears against the guide 40, while the inclined surfaces are engaged by gib 52 slidable along the side walls of the guide 40 and adjustable by 15 means of screws 53, 54 arranged in pairs, the screws 53 being in threaded engagement with the gib, and the screws 54 in threaded engagement with the guide 40. By adjusting one gib 52 up and the other one down, 20 the slide 39 may be shifted laterally in the guide 40, and by using different adjustments at opposite ends of the gib, the slide 39 may be caused, if desired, to reciprocate in a path forming a slight angle with the center 25 line of the guide 40.

On the tubular frame portion 20, adjacent to the upper bearing 21, is secured a ring 55, as by means of screws 56, and this ring is provided with as many radial sockets 55' 30 as there are slides 39 and tools 45 (eight in the case illustrated), each socket being threaded to receive adjustably a center pin 57, held, after adjustment, by means of a set screw 58. The pin 57 is adapted to support 35 the inner end of a blank carrier 59 having a suitable socket 59' to receive the pin, a shoulder 60' against which the blank 60 may be pressed by the action of a nut 61 screwing on the threaded end of the carrier, and a 40 key 62 for positively locking the blank 60 (provided with a corresponding key-way) against rotation relatively to the carrier. At its outer end, the carrier 59 has secured to it a toothed head or gear 63, having teeth 45 of the shape shown in Fig. 7, to mesh with gear openings or sockets 43' in the tool carrier or turntable 43, said gear sockets being of the shape shown in Figs. 1, 5, and 6. Of course, any other suitable gearing may be 50 employed to cause the blank carriers 59 to be rotated in the proper manner as the tool-carrying table 43 revolves. The outer end of each carrier 59 has an axial socket 59' to receive the end of a center pin 64, generally 55 stationary, but capable of a radial sliding movement in a portion 65 of the frame. The frame also has a cylindrically curved guide or index socket 65' (Figs. 1 and 1') for each of the carriers 59, to assist the operator in properly positioning the carriers. The pin 64 is normally pressed inward 60 against the blank carrier 59 by a screw 66 fitted to an internal thread in a bow 67 pivoted to the frame about a vertical axis 68. The screw 66 is provided with a hand wheel 65

69, and may be locked after adjustment, as by splitting the outer end of the socket 67' receiving said screw, and placing a nut 70 on the split portion of said socket. In order to allow the center pin 64 to be released 70 quickly when desired, said pin is provided with a transverse projection 64' the ends of which enter cam grooves 67'' of the bow 67. Fig. 2^a shows the two positions of the bow 67. In one position, the bow stands radially 75 with respect to the shaft 22, and the short straight portions 67* at the ends of the cam grooves 67'' are also radial, so that the pin 64 may be locked and (if required) may receive its final adjustment by turning the 80 screw 66 inwardly to the position shown in full lines in Fig. 2^a. When it is desired to release the pin 64, the screw 66 is turned outwardly to allow its inner end to clear the edge or "corner" at the outer end of the 85 pin 64 when the bow 67 swings on its axis 68, and then the bow 67 is swung laterally to the oblique position shown by dotted lines in Fig. 2^a, the cam grooves 67'' operating to slide the pin 64 outward so as to fully release the carrier 59 and the blank 60 thereon. A quick release of the blank and of its carrier is thus obtained. The radial groove portions 67* may be dispensed with, the position of the pin 64 being fully determined 95 by the engagement of its inner end with the socket 59' and of its transverse projection 64' with the cam grooves 67'', the screw 66, when in its inner position, serving to lock the cam bow 67 against swinging on its axis 100 68, which swinging movement would produce an outward movement of the pin 64. Figs. 1 and 8 show that the frame has an opening under the center pins 57, 64, for the convenient insertion and removal of the 105 carriers 59 with their blanks 60. Preferably, the frame has an inclined (conical) surface 71 to catch the chips and grit resulting from the cutting operation, and to discharge them at a point where they will 110 not injure the machine.

Any suitable mechanism may be provided for rotating the turntable 43, but I prefer to provide a mechanism which will cause the turntable to rotate at a relatively low rate 115 of speed during the cutting operation of the tools, and at an increased speed between cutting operations. The drawings show the following arrangement for this purpose: The turntable 43 has spur teeth 43* in mesh with a pinion 72 secured to a vertical shaft 73 journaled in an upper bearing 74 on the frame and in a lower bearing 75' extending from a stationary gear box 75. To the shaft 73 is secured a disk 76 carrying a peripheral cam 77 and an internally toothed disk or ring 78. This ring is in mesh with a pinion 79 secured to a shaft 80, the upper portion of which is journaled in a bearing 81 carried by the gear box 75, while the lower end of 120 125 130 135

said shaft is received in an axial socket 82' of a vertical shaft 82 alining with the shaft 80. To the shaft 82 is secured a sleeve 83 journaled in a bearing 75' projecting downwardly from the gear box 75; with the upper end of the sleeve 83 are connected sockets 83' in which are rigidly secured vertical pins or studs 84 on which pinions 85 are mounted to turn. Cotter pins 86 or 10 equivalent devices serve to hold the pinions 85 against longitudinal movement. The pinions 85 mesh with a central pinion 87 held to turn with the shaft 80, and also mesh with an internally toothed ring 88' secured to a disk 88 which is loosely mounted on said shaft 80. With the shaft 80 and pinion 87 is also mounted to turn a ratchet wheel 89, while a plate 83" integral with the sleeve 83 carries spring pawls 89' so arranged that rotation of the shaft 82 (which revolves continuously in one direction) will tend to drive the ratchet wheel 89 and the shaft 80 at the same speed as the shaft 82, the disk 88 in this case rotating idly in unison with the shaft 80. By holding the disk 88 stationary, the pinions 85 will be caused to roll upon the toothed ring 88' as the sleeve 83 revolves with the shaft 82, and the action of said pinions on the central pinion 87 will 25 cause the latter and the shaft 80 to rotate at a higher rate of speed than the shaft 82, the spring pawls 89' in this case slipping over the teeth of the ratchet wheel 89 which at that time is rotating faster than the sleeve carrying the pawls. In order to hold the disk 88 stationary at certain times, said disk is made with teeth 88" adapted to be engaged by a locking lever 90 fulcrumed on the gear box 75 at 90° and extending through 30 an opening 75" of said gear box. A spring 91 tends to throw the lever 90 into the locking position. The upper end of the lever is pivotally connected at 90" with an arm 92 connected with a slide 93 movable in a guide 45 disposed on top of the gear box 75 in a direction radial with respect to the shaft 73. The slide 93 is formed with an upwardly extending pin or stud 93' on which is mounted a roller 94 adapted to engage the cam 77. The shaft 82 is driven in any suitable manner, as by means of a belt 95 engaging a pulley 96 on the shaft 82 and another pulley 97 secured to the bevel wheel 23 on shaft 22.

To partly balance the weight of the guide 40 and slide 39, I prefer to provide springs 98 coiled around rods 99 secured to the turntable 43. The nuts 100, adjustable on said rods, form stops limiting the upward movement of the guide 40.

The specific machine described above is intended for cutting the teeth of pinions adapted to mesh with gears of the character shown in Figs. 14 and 15. These gears, 60 which are described more fully in my other

application referred to above, are gears in which the opposing surfaces 101, 101' of each two adjacent teeth are plane and have longitudinal lines or elements parallel to each other, being parallel to the axes 102 disposed centrally between said opposing tooth surfaces, and converging from the pitch circle 103 to a point 104 on the axis of the gear. In the particular case illustrated by Figs. 1 to 11, the working surfaces 75 or edges of the tool 45 are shaped and situated relatively to each other, exactly like the pair of surfaces 101, 101' on two adjoining teeth of the gear with which the pinion to be cut is to mesh. In other words, 80 in this particular case, the shape of the pinion cutter 45 is the same as the shape of the space between two adjacent teeth of the corresponding gear.

The blank 60 to be cut into a pinion may 85 be roughly formed in any suitable manner before being finished on my improved machine, that is to say, the said blank may be, and preferably is, a toothed blank when it is applied to the carrier 59. In practice it 90 will be advisable to provide twice as many carriers 59 as the machine is adapted to hold, that is to say, sixteen carriers in the case of a machine for cutting eight pinions at the same time, as in the machine illustrated. Thus, while the cutting operation is 95 going on, additional blanks 60 could be fastened on the extra carriers so that upon the completion of the cutting operation, these extra carriers could be placed in the machine at once, after removing the carriers with the finished pinions. The manner of inserting and removing the blank carriers 59, and of moving the center pins 64 for this purpose, will be evident from the description given above.

The rotation of the shaft 22 will cause the slides 39 and the tools 45 to reciprocate, the paths of the tools or cutters corresponding to straight axial lines (such as 102 in Figs. 14 and 15) of pairs of tooth surfaces (such as 101, 101') of the gear with which the pinions are adapted to mesh. While the tools are thus reciprocating, they also are traveling around the axis of the turntable 110 115 or tool carrier 43. The rotation of the turntable 43, produced by its meshing with the driving pinion 72, will (owing to the meshing of said turntable with the toothed heads 63 of the carriers 59) cause the blanks 60 to turn with the carriers 59, at the same rate 120 relatively to the circumferential movement of the tools 45 as the rate at which the finished pinion will turn relatively to the gear with which it is intended to mesh in actual use. The toothed head 63 preferably has the same number of teeth as the pinion to be cut. When one of the tools 45 has finished cutting a tooth on one of the blanks 60, such tool, by the rotation of the turntable 43, is 125 130

brought into operative relation to the blank 60 on the next carrier 59, and this operation being repeated a suitable number of times, all the teeth of the several pinions are completed. It will be understood that the several tools 45 occupy similar positions at all times, to the several blanks 60, that is to say, all cutters 45 begin to cut at the same time, and all of them stop cutting at the same time. It will be evident that time may be saved by speeding up the turntable 43 during the intervals when the cutting tools 45 are passing from one blank 60 to the next, and for this purpose I have provided the speed-changing mechanism governed by the disk 76 and cam 77. As long as the cutters 45 are operating on the blanks 60, the cam 77, by engaging the roller 94, holds the lever 90 out of engagement with the teeth 88" of the disk 88, so that the shaft 80 rotates at the same (relatively low) speed as the shaft 82. At those times when the tools 45 are not cutting, the roller 94 (having passed beyond the cam 77) engages the disk 76, and the lever 90 is in locking engagement with the disk 88, so that the shaft 80 will rotate at a higher rate of speed than the shaft 82. Of course, the pinion 72 has such a number of teeth that (counting from the time the tool 45 begins to operate on one blank) a complete revolution of said pinion will bring the tool 45 into proper position to begin the cutting operation on another blank, preferably the next blank; thus, with eight tools as shown, the pinion 72 will have a number of teeth equal to one-eighth the number of teeth 43" (as shown), or a multiple of such one-eighth. Of course, the turntable 43 might be rotated continuously at a uniform rate of speed, both during the cutting operations and during the intervals when the tools 45 are passing from one blank 60 to another.

In order that the machine may complete the cutting of all the teeth of the pinions without any readjustments of its parts and particularly of the blank carriers 59, it is desirable that the number of teeth on the head 63, and the number of the mating tooth sockets 43" on the turntable 43, should have no common divisor or factor. Stated broadly, in order to secure this advantage, the angular distance between any two tools 45, measured by the corresponding number of teeth sockets 43", should have no divisor or factor in common with the number of teeth on the head 63. When, as in the case illustrated, the tools 45 are spaced evenly around the machine, the rule will be as follows: The number of teeth on the head 63 should have no common divisor or factor with the quotient obtained by dividing the total number of tooth sockets 43" by the number of tools. In each of these rules, it should be noted that the number of teeth on

each of the heads 63 has been assumed as equal to the number of teeth on each of the blanks or pinions 60. Of course, in practice, the even spacing of the several tools will be preferred. Thus, in the example shown, the head 63 (and the blank 60) has thirteen teeth, and the turntable 43 is supposed to have forty-eight tooth sockets 43"; as the eight tools 45 are evenly spaced, the angular distance between adjacent tools 45 is represented by six tooth sockets 43". Now, the numbers 6 and 13 have no common divisor. Therefore, if one of the tools 45 cuts say, the first tooth of a pinion 60, the next tool 45 will operate on the seventh tooth of the same pinion, the next tool on the thirteenth tooth, the next on the sixth, and so on (twelfth, fifth, eleventh, fourth, tenth, third, ninth, second, and eighth tooth) until every tooth has been cut. From the explanation just given, it will be apparent that the turntable 43 will have to perform more than a complete revolution (to wit, one and five-eighths of a revolution) in order to cut all the (thirteen) teeth of each blank or pinion 60.

In the example shown, the blank carriers 59 are equal in number to the tools 45 and evenly spaced (at intervals of 45° , corresponding to six tooth sockets 43"). This even spacing of the blank carriers is essential when the turntable is rotated alternately fast and slow, as in the specific example described above, but if the turntable is rotated at a uniform rate of speed, it is immaterial whether the blank carriers 59 are spaced evenly or not.

The various adjustments described above enable the cutters 45 and their slides 39 to be set so that the tools will travel in the proper paths. In cutting bevel pinions with radial teeth (Figs. 1 to 11), since the oblique cutting edges of the tool do not lie in the central line or plane of the slide 39, said edges will operate in planes which do not pass through the vertex of the cone of the blank or pinion 60. This will be understood best by reference to Figs. 1 and 4. A indicates the axes about which the respective blanks 60 are adapted to rotate, and B the axis about which the turntable 43 rotates. The said axes A and B intersect at the point C, which is also the vertex of the blank cone (indicated by the diverging lines D) and of the cone (indicated by the diverging lines E) corresponding to the pitch cone of the gear with which the pinion is to mesh. The path of reciprocation forms acute angles with both axes A, B. It will be seen that the direction in which a tool 45 reciprocates, is parallel with a line (such as D, E) running to the vertex C. Fig. 4 being a view perpendicular to the direction in which the tool reciprocates, it follows that the tool will reciprocate in a direction perpendicular to the

plane of the drawing (with respect to Fig. 4), that is to say, each of the two straight cutting edges of the tool 45 will move in a plane perpendicular to the plane of the paper. It will be obvious that these planes of motion do not pass through the vertex C, for in Fig. 4 this vertex is projected into the point C', which lies between the cutting edges of the tool.

10 It is to be noted that in the example shown I employ a tool or cutter having straight cutting edges, and cause this tool to reciprocate along a straight line corresponding (or parallel) to the axis (102) of that pair of 15 tooth surfaces of the mating wheel of which said tool is a counterpart; I am thus able to form conjugate pinion surfaces to such plane surfaces (101, 101') of the mating wheel.

20 In speaking above of the tool as reciprocating along a straight line, I was leaving out of consideration, for the moment, the fact that simultaneously with its reciprocation, the tool also travels about the axis B 25 with the turntable 43. The relative motions however are so determined that the speed of the tool's reciprocation will be so much greater than that of the movement about said axis B, that the amount of circumferential shifting of the tool during a single cut (inward motion) will be very slight and practically negligible. The gearing may be so proportioned, for instance, that each tool 30 will perform say twenty-five cuts on a pinion 35 tooth before such tooth passes out of the operative range of the tool.

While the cutter shown in Figs. 1, 3, 4 and 16 is adapted to cut a pinion which will mesh with a gear in which the space between 40 two adjoining teeth is of uniform cross section (since the tooth surfaces 101, 101' are parallel to the axial line 102), so that the pinion cutter will cut at the same time, the two surfaces of the same tooth (see Fig. 4), 45 it may be desired in some cases to cut the opposing surfaces of two adjoining pinion teeth at the same time, viz.: when the teeth (and not the spaces) of the meshing gear are of uniform cross section. All that is necessary 50 in this case is to employ a cutter such as shown in Fig. 17, which has two straight cutting edges 45* converging toward the free end of the tool and thus adapted to cut at the same time, the opposing tooth surfaces 55 of two adjoining pinion teeth.

In some cases it may not be desirable to cut two tooth surfaces at the same time. For this purpose, I may provide cutters of the type shown in Figs. 18 and 18^a, having 60 only one straight cutting edge 45^a, which on one cutter slants to the left, and on the other tool to the right. Preferably, the tools shown in Figs. 18 and 18^a (and also in Fig. 17) would in all other respects be made exactly like the tool 45 of Figs. 1, 3, and 4, so

as to be interchangeable therewith. When employing the tools shown in Figs. 18 and 18^a, I would prefer to secure tools such as shown in Fig. 18, in alternate tool holders or slides 39, that is to say, one slide would 70 carry a tool of the form shown in Fig. 18, the next a tool of the shape shown in Fig. 18^a, and so on. In this case, it would of course take longer (three and one-fourth revolutions of the turntable 43) to complete 75 the cutting operation than when each cutter has two cutting edges operating simultaneously, as in the form of cutter shown in Figs. 1, 3, and 4.

The pinion produced by the operation of 80 the machine as described above has tooth surfaces, formed by the action of the straight cutting edges reciprocated in paths which correspond to the axial or central lines (such as 102) of a pair of tooth surfaces on the gear 85 with which said pinion is adapted to mesh. The planes of reciprocation of these cutting edges are tangent to the tooth surfaces which they cut on the pinions, and as stated above, such planes do not pass through the vertex 90 C of the pitch cone of the blank. At each reciprocation, the edge of the cutter produces a straight-line element on the tooth surface. Inasmuch as the tool carrier rotates, the straight lines produced on the 95 same tooth surface by successive cuts will all extend in different directions, that is to say, each of the straight-line elements on a particular tooth surface forms an angle with all the other straight-line elements on the same 100 tooth surface of the blank or pinion, or, in other words, no two straight-line elements on the same tooth surface will be parallel to each other. On the other hand, there will be on each tooth surface of the pinion, a 105 straight line (and only one) which is parallel to just one straight line on an adjacent tooth surface. In the particular case when both surfaces of the same tooth are cut in the fashion described (Figs. 1, 3, 4, 18, and 18^a), one of such pair of parallel lines will be on one tooth surface of a tooth, and the other on the other surface of the same tooth. When however, the cutters are arranged to 110 cut opposing surfaces of adjoining teeth (Fig. 17), the pair will be, not on the two surfaces of the same tooth, but on the opposing surfaces of adjoining teeth. In each case, of course, the pair of parallel straight-line elements will be on adjacent or immediately 115 successive tooth surfaces of the pinion. These lines will also, of course, appear parallel if viewed in projection toward the axis of the blank. From Fig. 4 it will be seen that the cutting edges of the cutter 45 are arranged on opposite sides of the center line (indicated by the point C') of the reciprocatory motion. The same thing would be 120 true of a cutter such as shown in Fig. 17, or a set of cutters such as shown in Figs. 18 125

and 18^a. In each case, the plane of reciprocation of the cutting edge, does not pass through the vertex of the pitch cone of the blank and every point of each of the two cutting edges reciprocates in a path which does not intersect the axis of the blank.

During the inward movement of each cutter, the pull of the connecting rod 32 on the pin 36, arranged interiorly of the line of the trunnions 41*, will swing and hold the guide 40 down against the inner (inclined) supporting surface 43' of the turntable 43; but during the outward (return, inactive) movement, the push of the connecting rod, assisted by the springs 98 when such are employed, will cause the tool to rise, by swinging the guide 40 upwardly against the (adjustable) stops 100.

The wear of the cutters will generally not affect their operation, but when it becomes necessary to adjust them considerably lengthwise of their path, I may disconnect the plate 36' and reverse it, bringing what was formerly its inner end to the outside, and owing to the unsymmetrical arrangement of the pin 36 such reversal will have the same effect as if the length of the connecting rod 32 were altered.

Upon disconnecting the rods 32, the guides 40 with the parts carried thereby may be swung outwardly on the trunnions 41* until the normally upper surface of the guides (which surface by this movement becomes the lower surface) rests on a supporting surface 43^a located exteriorly of the axis of the trunnions 41*. This is of great convenience not only for getting at the cutters 45 (which are thus exposed), but also for removing the shaft 22 if desired, and also for applying in the central space of the frame, a suitable gage for properly positioning the cutters. The dotted lines at the left of Fig. 1 indicate the position taken by the guide 40 when swung through an angle of over 180° so as to bring it to rest on the exterior supporting surface 43^a.

When the cutter has two cutting edges as in Figs. 1, 3, 4 and 17, such edges are preferably located in the same plane, which is transverse to the path in which the tool reciprocates. Obviously, the angle subtended by the two cutting edges (viewed from the axis) increases as the tool moves inward. The pinion tooth produced by the cutter is not of uniform cross section from end to end, but narrower at that end which is nearer to the axis of the pinion. In Fig. 13, the heavy line indicates the inner or smaller end of the pinion, and the light line, the outer end.

In the machine shown, the angle between the axis of the turntable 43 and the axes of the blank carriers 59 is a right angle, the blank carrier axes being horizontal, and the axis of the turntable vertical. This right-

angle arrangement, of course, is not essential to my invention, being employed only when the pinion and the wheel with which it is to mesh, are to rotate about axes perpendicular to each other.

As has been stated hereinabove, the arrangement shown in Figs. 2 and 4 enables the path of the slide 39 to be adjusted slightly to one side so that the direction of said path may be at a slight angle to the normal position, so that the said path (that is to say, the path of the slide's center) will not intersect the axis B; in this case, the teeth cut will not be "radial," but skew teeth. When the skew angle is greater than the range of lateral adjustment of the slide path in the construction shown in Figs. 2 and 4, I may employ the special guide 40* shown in Fig. 19. This guide differs from the one shown in the other figures, simply by the fact that the guideway on which the slide 39 moves, extends obliquely to the axis of the trunnions 41*, and not at right angles to said axis. Fig. 19 also shows the general shape of skew bevel teeth which will be cut on the blank 60' with this arrangement. It will be understood that all the other parts are the same as in the construction first described, that is to say, the substitution of guides 40* for the guides 40 is the only change required. What I have stated above concerning the existence of parallel straight-line elements on two adjacent tooth surfaces, is true in the case of skew bevel teeth also, except that only the projections (toward the pinion axis) of two straight-line elements on adjacent tooth surfaces will be parallel, and not these elements themselves.

The relative motion of the blank and of the tool edge operating on said blank, is the same as the motion which the tooth surfaces of the pinion, when finished, will have with reference to the gear meshing with such pinion. This motion may be termed a rolling contact motion, which motion is composed of two rotary motions about different axes, which in the particular case illustrated by the drawings, are designated as A and B respectively. The path of the tool's reciprocation is oblique to both axes of said rolling contact motion.

While I have shown each of the blanks rotating about a stationary axis, and the tool reciprocating on a carrier which revolves about another axis, it will be obvious that the arrangement might be varied without affecting the relative motion of the parts, and I desire it to be understood that such cinematic equivalents are within the scope of my invention. Modifications of this nature, and others, may be made without departing from the nature of my invention as set forth in the appended claims.

I claim as my invention:

1. A machine for cutting bevel gears, the

axes of which intersect, comprising a blank carrier, and a tool arranged to reciprocate in such a path that its cutting edge will describe a surface having no straight-line elements which pass through the vertex of the pitch cone of the blank, and means for producing a relative rolling motion of the tool and the blank.

2. A machine for cutting bevel gears, comprising a blank carrier, a tool carrier, a tool secured on said carrier, means for reciprocating the tool carrier and the tool so as to cause the latter to cut on the blank, straight-line tooth-surface elements which do not pass through the vertex of the blank cone, and means for producing a relative rolling motion of the blank and tool.

3. A gear-cutting machine, comprising a blank carrier, a tool holder, a tool carried thereby, means for producing a relative rolling motion of the tool and the blank, and means for imparting a reciprocating motion to said tool in a direction oblique with reference to the axes of said rolling motion, said tool having two cutting edges out of longitudinal alinement with reference to the direction of reciprocation, said cutting edges being adapted to form on the blank simultaneously, tooth-surfaces having rectilinear elements lying out of axial planes of the blank.

4. A gear-cutting machine, comprising a blank carrier, a tool carrier, a tool on the last-named carrier, means for producing a relative rolling motion of the tool and blank, said tool having two cutting edges in constant operative relation to each other and formed in counterpart to two adjacent tooth-surfaces, and means for reciprocating said tool in a direction oblique with reference to the axes of said rolling motion, to simultaneously cut two tooth-surfaces on the blank.

5. A machine for cutting bevel gears, comprising a blank carrier, a cutting tool having two cutting edges located symmetrically on opposite sides of a plane which contains the axis of the blank carrier, means for reciprocating said tool so that every point of said cutting edges will move in a path parallel to said plane, and means for producing a relative rolling motion of said tool and of the blank on the blank carrier.

6. A machine for cutting bevel gears, comprising a blank carrier, a tool, means for producing a relative rolling motion of the tool and of the blank held on said carrier, about intersecting axes, and means for causing the cutting edge of the tool to reciprocate in a plane which does not pass through the point of intersection of said axes.

7. A machine for cutting bevel gears, comprising a blank carrier, a tool, means for producing a relative rolling motion of the tool and of the blank held on said carrier, about two intersecting axes one of which coincides

with that of the carrier, and means for causing the tool to reciprocate in such a direction that all points of its cutting edge will describe paths which do not intersect the said axis of the carrier.

8. A gear-cutting machine, comprising a blank carrier, a tool, means for producing a relative rolling motion of the tool and of the blank about two axes one of which coincides with that of the carrier, and means for reciprocating the tool obliquely with reference to the axis of the carrier in such a direction that all points of the tool's cutting edge will describe paths which do not intersect the said axis of the carrier.

9. A gear-cutting machine, comprising a blank carrier, a tool having two cutting edges which are nearer to each other at one end than at the other, means for producing a relative rolling motion of the tool and of the blank held on said carrier, about two axes one of which coincides with that of the carrier, and means for reciprocating the tool obliquely with reference to the axis of the carrier in such a direction that all points of both cutting edges of the tool will describe paths which do not pass through the said axis of the carrier, said cutting edges being out of longitudinal alinement with reference to the direction of reciprocation.

10. A machine for cutting gears, comprising a blank carrier and a tool carrier arranged to rotate, one relatively to the other, a tool holder on the tool carrier, arranged to reciprocate in a path which is oblique to the axes of both carriers, a tool in said holder arranged to reciprocate therewith in such a direction that all points of the cutting edge of the tool will move in paths which do not intersect the axis of the blank carrier and driving means for causing the tool to follow said relative rotation.

11. A bevel-gear cutting machine, comprising a rotary blank carrier, a tool carrier, a cutting tool carried by the last-named carrier and rotated to follow the rotation of the blank, and reciprocated with reference thereto in such a manner that the cutting edge of said tool will move in planes which do not pass through the vertex of the pitch cone of the blank, said blank carrier and the tool carrier having axes which intersect, and driving means for effecting said rotation and reciprocation.

12. A gear-cutting machine comprising a rotary blank carrier, a tool carrier mounted to turn about an axis forming an angle with that of the blank carrier, a tool holder arranged to turn with said tool carrier and to reciprocate thereon lengthwise of the blank carrier, in a direction forming an acute angle with the axis about which the tool carrier turns, and means for producing in unison, a rotation of the blank carrier and of

- the tool carrier and a reciprocation of the tool holder.
13. A gear-cutting machine comprising a rotary blank carrier, a tool carrier mounted to turn about an axis at an angle to that of the blank carrier, a tool holder arranged to turn with said tool carrier and to reciprocate relatively thereto toward and from the central portion of the carrier, in a direction oblique to the axis of rotation of the blank carrier, and means for producing in unison, a rotation of the blank carrier and of the tool carrier and a reciprocation of the tool holder.
14. A gear-cutting machine comprising a rotary blank carrier, a tool carrier mounted to turn about an axis at an angle to that of the blank carrier, a tool holder arranged to reciprocate toward and from the central portion of the tool carrier and to rotate with said tool carrier, and means for producing in unison, a rotation of the blank carrier and of the tool carrier and a reciprocation of the tool holder.
15. A machine for cutting bevel pinions, comprising a rotary blank carrier, a tool holder arranged to reciprocate in a path at an angle to the carrier's axis, a tool carried by said holder and having two cutting surfaces shaped conformably to the teeth of the bevel wheel with which the pinion being cut is adapted to mesh, and means for causing the tool holder to receive a rolling motion relatively to the blank carrier.
16. A gear-cutting machine comprising a blank carrier, a tool holder, a tool carried by said holder and provided with a cutting edge, means for producing a rolling contact motion between the blank held on said carrier and the tool carried by said holder, and means for reciprocating said holder in a direction oblique with reference to the two axes of said rolling contact motion and in such a manner that all points of the cutting edge of the tool will move in paths which do not intersect the axis of the blank carrier.
17. A gear-cutting machine comprising a blank carrier, a tool having two cutting edges, a holder for said tool, means for producing a rolling contact motion between the blank held on said carrier and the tool carried by said holder, and means for reciprocating said holder in a direction oblique with reference to the two axes of the said rolling contact motion and in such a manner that all points of the cutting edge of the tool will move in paths which do not intersect the axis of the blank carrier.
18. A gear-cutting machine comprising a blank carrier, a tool holder, a tool on said holder, means for producing a rolling contact motion between the blank held on said carrier and the tool carried by said holder, and means for reciprocating said holder in a direction oblique with reference to the two axes of the said rolling contact motion and in such a manner that all points of the cutting edge of the tool will move in paths which do not intersect the axis of the blank carrier.
19. A gear-cutting machine comprising a blank carrier, a tool having two simultaneously operative converging cutting edges lying in the same plane, means for producing a rolling contact motion between the said tool and the blank held on said carrier, and means for reciprocating the tool at an angle to both axes of said rolling contact motion and also at an angle to the plane of said cutting edges in such a manner that the said cutting edges will move in planes which do not pass through the vertex of the pitch cone of the blank.
20. A gear-cutting machine comprising a blank carrier, a tool having two simultaneously operative converging rectilinear cutting edges, means for producing a rolling contact motion between said tool and the blank held by said carrier, and means for reciprocating the said tool at an angle to both axes of the said rolling contact motion and also at an angle to the plane of said cutting edges in such a manner that the said cutting edges will move in planes which do not pass through the vertex of the pitch cone of the blank.
21. A gear-cutting machine comprising a blank carrier, a tool having two simultaneously operative cutting edges which are closer together at one end than at the other, means for producing a rolling contact motion between the said tool and the blank held on said carrier, and means for reciprocating the tool at an angle to both axes of the rolling contact motion in such a manner that all points of said cutting edges will move in lines which do not pass through the vertex of the pitch cone of the blank.
22. A gear-cutting machine comprising a blank carrier, a tool having two simultaneously operative cutting edges located in the same plane, means for producing a rolling contact motion between the said tool and the blank held on the carrier, and means for reciprocating the tool at an angle to both axes of the rolling contact motion and also at an angle to the plane of the cutting edges in such a manner that all points of said cutting edges will move in lines which do not pass through the vertex of the pitch cone of the blank.
23. A machine for cutting bevel gears, comprising a plurality of rotary blank carriers radiating from a common center, a tool carrier arranged to rotate about an axis passing through said center, tool holders mounted to reciprocate on said tool carrier lengthwise of the blank carriers, and means for causing the tool holders to reciprocate.

simultaneously with the rotation of the blank carriers and of the tool carrier.

24. A machine for cutting bevel gears, comprising rotary blank carriers radiating from a common center, tool holders arranged to reciprocate lengthwise of said carriers, and means for causing said holders, as they reciprocate, to revolve bodily about an axis passing through said center.

10 25. A machine for cutting bevel gears, comprising rotary blank carriers radiating from a common center, a tool carrier mounted to turn about an axis passing through said common center and forming equal angles with the axes of the several blank carriers, tool holders mounted to reciprocate on said tool carrier lengthwise of the blank carriers, and means for causing the tool holders to reciprocate simultaneously with the rotation of the blank carriers and of the tool carrier.

25 26. A machine for cutting bevel gears, comprising rotary blank carriers radiating from a common center, a tool carrier connected with said blank carriers by meshing teeth thereon and mounted to turn about an axis passing through said common center, tool holders mounted to reciprocate in and out on said carrier and arranged at angular intervals so proportioned that the number of teeth on the carrier, between any two tool holders, and the number of teeth on each of the blank carriers, will have no common divisor, and means for causing the tool holders to reciprocate simultaneously with the rotation of the blank carriers and of the tool carrier.

40 27. A machine for cutting gears, comprising a rotary blank carrier, a tool carrier connected with said blank carrier by meshing teeth thereon, tool holders mounted to reciprocate in and out on said carrier and arranged at intervals so proportioned that the number of teeth on the carrier, between any two tool holders, and the number of teeth on the blank carrier, will have no common divisor, and means for causing the tool holders to reciprocate simultaneously with the rotation of the carrier.

50 28. A machine for cutting gears, comprising a blank carrier and a tool carrier connected by toothed gearing, in such a manner as to produce a rolling contact motion between said carriers, a tool holder arranged to reciprocate on the tool carrier at an angle to the axes of both carriers and a tool secured to said holder and having a cutting edge all points of which reciprocate in paths which do not intersect the axis of the blank carrier.

60 29. A machine for cutting gears, comprising a blank carrier and a tool carrier connected by meshing teeth thereon in such a manner as to produce a rolling contact motion

between said carriers, tool holders mounted to reciprocate in and out on said tool carrier and arranged at intervals so proportioned that the number of teeth on the carrier, between any two tool holders, and the number of teeth on the blank carrier, will have no common divisor, and means for causing the tool holders to reciprocate simultaneously with the rolling contact motion between the carriers.

30. A gear-cutting machine, comprising a blank carrier, a tool holder, a tool carried by said holder and provided with a cutting edge, means for producing a rolling contact motion between the blank held on said carrier and the tool carried by said holder, and means for reciprocating said holder in a direction oblique with reference to the two axes of the rolling motion, at a speed so much greater than that of the rolling motion that the amount of circumferential shifting of the tool during a single cut will be practically negligible, the direction of the reciprocation being such all points of the cutting edge will move in lines which do not pass through the vertex of the pitch cone of the blank.

31. A machine for cutting gears, comprising a frame, a center pin adapted to engage one end of a blank carrier, a mating center pin for engaging the other end of the blank carrier, screw mechanism for the slow adjustment of the last-named center pin, cam mechanism for the quick adjustment of said pin, and means for cutting tooth surfaces on the blank while held by said center pins.

32. A machine for cutting gears, comprising a blank carrier, a tool carrier, a guide pivoted to the tool carrier, a tool-holding slide arranged to reciprocate on said guide in a direction transverse to the pivot axis of the guide, and means for imparting a relative rolling contact motion to the blank held on the blank carrier and to the tool carried by said slide.

33. A machine for cutting gears, comprising a blank carrier, a tool carrier, a guide pivoted to the tool carrier, a guide slide arranged to reciprocate on said guide in a direction transverse to the pivot axis of the guide, means for limiting the movement of the guide about its pivot, and means for imparting a relative rolling contact motion to the blank held on the blank carrier and to the tool carried by said slide.

34. A machine for cutting gears, comprising a blank carrier, a tool carrier, a guide pivoted to the tool carrier about a horizontal axis, a tool-holding slide arranged to reciprocate on said guide in a direction transverse to the pivot axis of the guide, means tending to swing the said guide upwardly on its pivot, and means for imparting a relative rolling contact motion to the

blank held on the blank carrier and to the tool carried by said slide.

35. A machine for cutting gears, comprising a blank carrier, a tool carrier, a guide pivoted to the tool carrier and adjustable lengthwise of its pivot axis, a tool-holding slide arranged to reciprocate on said guide in a direction transverse to said pivot axis, and means for imparting a relative rolling contact motion to the blank held on the blank carrier and to the tool carried by said slide.

36. A machine for cutting gears, comprising a blank carrier, a tool carrier, a guide pivoted to the tool carrier, the latter being provided, on opposite sides of the guide's pivot, with supporting surfaces arranged to engage the guide in two different positions, a tool-holding slide arranged to reciprocate on said guide in a direction transverse to said pivot axis, and means for imparting a relative rolling contact motion to the blank held on the blank carrier and to the tool carried by said slide.

37. A machine for cutting gears, comprising a blank carrier, a tool carrier mounted to turn, a plurality of guides which are pivoted to the tool carrier to swing about horizontal axes, the said tool carrier being provided, both interiorly and exteriorly of said pivot axes, with supporting surfaces arranged to engage the guides in their normal and in their inverted positions respectively, tool-holding slides arranged to reciprocate on said guides in directions transverse to the respective pivot axes, centrally located driving mechanism having detachable connections with said slides, and means for imparting a relative rolling contact motion to the blank held on the blank carrier and to the tools carried by the said slides.

38. A machine for cutting gears, comprising a blank carrier, a tool carrier mounted to turn about an upright axis, a guide pivoted to said tool carrier about a horizontal axis located at the outer portion of the guide, a tool-holding slide arranged to reciprocate on said guide in a direction transverse to said horizontal axis, driving means connected with said slide at a point located interiorly of the said horizontal axis, and means for imparting a relative rolling contact motion to the blank held

on the blank carrier and to the tool carried by the said slide.

39. A machine for cutting gears, comprising a frame provided with an index socket adapted to engage a blank carrier, center pins carried by said frame adjacent to said index socket and adapted to engage the ends of the blank carrier, and means for cutting tooth surfaces on the blank while its carrier is positioned by said index socket and held by said center pins.

40. A machine for cutting gears, comprising a blank carrier, a rotary tool carrier, tool holders arranged to rotate with said tool carrier and arranged to reciprocate thereon to cut tooth surfaces on the blank, and means for rotating the tool carrier alternately slow and fast, corresponding respectively to the periods during which the cutting operation is proceeding and the intervals during which the tools exert no cutting action.

41. A machine for cutting gears, comprising a blank carrier, a rotary tool carrier, tool holders arranged to rotate with said tool carrier and to reciprocate thereon to cut tooth surfaces on the blank, means for rotating the tool carrier, and speed-changing mechanism, operated automatically as the tool carrier rotates, to cause the said carrier to move relatively slow during those portions of its revolution when the tools are cutting, and to be speeded up during those portions of the revolution of the tool carrier when the tools are not cutting.

42. A machine for cutting gears, comprising a blank carrier, a rotary tool carrier, a tool holder arranged to rotate with the tool carrier and to reciprocate thereon to cut tooth surfaces on the blank, means for rotating the tool carrier, and speed-changing mechanism, operated automatically as the said carrier rotates, for speeding it up during the intervals when the tool is out of contact with the blank.

In testimony whereof, I have signed this specification in the presence of two subscribing witnesses.

HARVEY D. WILLIAMS.
